UNITED STATES PATENT OFFICE.

FREDERICK WEINBERG, OF DETROIT, MICHIGAN.

VACUUM FEED APPARATUS.

1,302,610.

Specification of Letters Patent.

Patented May 6, 1919.

Application filed June 14, 1917. Serial No. 174,680.

To all whom it may concern:

Be it known that I, FREDERICK WEINBERG, a citizen of the United States, residing at Detroit, county of Wayne, State of Michigan, have invented a certain new and useful Improvement in Vacuum Feed Apparatus, and declare the following to be a full, clear, and exact description of the same, such as will enable others skilled in the art to which it pertains to make and use the same, reference being had to the accompanying drawings, which form a part of this specification.

My invention relates to vacuum feed apparatus and consists in the improvements hereinafter described and pointed out in the claims.

In the accompanying drawing:

Figure 1 is a side elevation, diagrammatic in character, of an apparatus embodying my invention.

Fig. 2 is a detail of the auxiliary tank partly in section.

Fig. 3 is a view similar to Fig. 2, the section being taken at right angles to that of Fig. 2, a special form of joining the constituent parts of the auxiliary tank being shown.

a is the engine and b is the crank case thereof. c is a centrifugal pump for circulating the cooling water. d is a pump for circulating the oil.

The auxiliary tank is made up of two shells e and f, the walls of which are joined at the open ends of said parts. In the form shown in Fig. 2, there are annular outwardly extending flanges around the open ends of said parts which are joined in the usual way, as shown. In Fig. 3 screw threads are indented or spun in the thin metal of the parts which are then screwed together.

There is a partition v consisting of a circular plate convex downward and having its edge held and bound between the constituent parts e f of the auxiliary tank so as to divide said tank into an upper chamber p and a lower chamber q. There is a casting r secured in a central aperture in the partition v and having two passages formed through it, one of which forms a communication or conduit between the chambers p and q and the other s opens at its lower end to the chamber q and is continued at its upper end in a pipe c² which passes up through the upper wall of the auxiliary reservoir and opens at its upper end to an opening communicating with the outer air through a passage in which is an inwardly opening

check valve n thus putting the compartment q into communication with the outer air so as to restore atmospheric pressure on said compartment.

k is a float in the chamber p, having a central aperture through which passes the tube c², which tube serves for a guide for the float k in its motion.

There is a hook k² extending from the upper surface of the float k. u² is an aperture in a casting in the upper wall of the auxiliary reservoir, said aperture having a valve seat around its inner end and communicating with a passage u.

t² indicates a valve seat around the upper end of the passage t.

m is a U-shape wire having the valves m² and m³ secured thereon. The hook k² engages the loop of the wire m and the valve m² is so located that when the float k rises it shall raise the wire m so as to engage the valve m² upon its seat u². When the float k falls the wire m is drawn downward by the float through the hook k² seating the valve m³ on the seat t².

x is a supply tank for liquid fuel located normally at a level below the auxiliary tank e f. x² is a conduit leading from the tank x to the auxiliary reservoir e f at x³. y is a deflecting plate secured to the delivery orifice for the liquid fuel and acting to carry such fuel beyond the float k so that it shall not fall upon said float.

z is a spring having its ends secured between the two parts e and f of the auxiliary reservoir and normally bent at its center so that it shall spring by an intermediate position because of its resilience. The center of the spring z engages the float k so that said spring acts in the usual way to positively force the float to one or the other extremes of its travel.

h is a pipe communicating with the passage u and with the intake to a pump c or d. The pipe h is shown in full lines as communicating with the intake of the pump c and it is indicated in dotted lines, as an alternative construction, at d⁴ communicating with the intake to the oil pump d.

2 is a pin or projection extending horizontally from the casting r. 3, 4 is a wire engaging the outer end of the projection 2 extending downward in the vertical part 3 then horizontally in the horizontal part 4 to engage the casting r. r² is a valve suspended upon the projection 2 and guarded by the wire 4.

The operation of the above described device is as follows:

When the engine is running the suction of the pump c or d closes the valve r^2 , draws a vacuum in the chamber p and causes the liquid fuel to rise from the tank x into the chamber p until the liquid in said chamber has acted upon the float k to cause it to draw the spring z beyond its central position 5 whereupon the float k rises suddenly and closes the valve m^2 upon its seat u^2 thus shutting off the communication with the vacuum producing means. Flap valve r^2 then opens and lets the liquid flow by gravity into the 10 chamber q . When the level of the liquid in the compartment p has fallen sufficiently the float k is carried to its lower position, as shown in Fig. 2, drawing the valve m^2 from its seat and the valve m^3 upon its seat thus 15 opening the vacuum producing passage and closing the communication with the outer air.

In internal combustion engines used with air planes or upon boats a high speed of 20 rotation is maintained constant and the pumps c and d will be driven at a high rate of speed and therefore their suction will be sufficient at all times to work the vacuum feed apparatus.

30 What I claim is:

1. In combination with a vacuum feed apparatus having a vacuum chamber, an internal combustion engine having a liquid circulating pump adapted to be actuated by the 35 same, and a vacuum producing passage communicating with said vacuum chamber and with the intake of said pump.

2. In a vacuum feed apparatus, an auxiliary reservoir consisting of two shells fastened together at their open ends, operating apparatus in said auxiliary reservoir, and a spring secured at its ends between said parts so that the spring shall be bowed between its 45 ends and adapted to actuate said operating apparatus in both directions.

3. In a vacuum feed apparatus, an auxiliary reservoir having a vacuum chamber, a vacuum producing passage communicating with said chamber, a passage communicating 50 with said chamber and with the outer air, a U-shape wire having two valves secured thereon, one of said valves being adapted to close the communication with the vacuum producing passage and the other of said 55 valves being adapted to close the passage to the outer air, said valves being so located on said wire that one shall be off its seat when the other is engaged upon its seat, and a float adapted to move said wire for the purpose 60 described.

4. In a vacuum feed apparatus, an auxiliary reservoir having a vacuum chamber, a

vacuum producing passage communicating with said chamber, a passage communicating with said chamber and with the outer air, 65 a U-shape wire having two valves secured thereon, one of said valves being adapted to close the communication with the vacuum producing passage and the other of said valves being adapted to close the passage to the outer air, said valves being so located on said wire that one shall be off its seat when the other is engaged upon its seat, and a float having a hook engaging the loop of said wire and adapted to actuate the wire for the 70 purpose described.

5. In a vacuum feed apparatus, an auxiliary reservoir having an upper and a lower chamber, a vent tube extending through said upper chamber and continuously communicating at its lower end with the lower chamber and at its upper end with the outer air, 80 and a float in said upper chamber, said tube acting as a guide for said float.

6. In a vacuum feed apparatus, an auxiliary reservoir consisting of two shells, the adjacent ends of said shells being provided respectively with complementary screw threads indented in the thin metal thereof, 85 said shells being secured together by screwing the ends together.

7. In an apparatus of the kind described, a part r having a projection 2 extending laterally therefrom, a valve suspended on said projection, and a wire engaging the outer 95 end of said projection extending downward outside of said valve then turning inward and engaging the part r below the valve r^2 .

8. The combination with a vacuum actuated apparatus of an internal combustion 100 engine having a water circulating system, a passage communicating with said water circulating system at a point where the pressure in said system is less than atmospheric pressure, said passage communicating with 105 said vacuum actuated apparatus for the purpose described.

9. In a vacuum feed apparatus, an auxiliary reservoir having an upper and a lower chamber, an intake passage for air to the 110 upper chamber and a tube extending through said upper chamber and communicating at its lower end with the lower chamber and at its upper end with the intake passage for air to the upper chamber.

10. In a vacuum feed apparatus, an auxiliary reservoir having an upper and a lower chamber, and a tube extending through said upper chamber and communicating at its lower end with the lower chamber and at its 120 upper end with the outer air.

In testimony whereof I sign this specification.

FREDERICK WEINBERG.
